F. K. LORD.
INTERNAL COMBUSTION ENGINE.
APPLICATION FILED NOV. 8, 1915.

Patented Aug. 21, 1917.

1,237,350.

UNITED STATES PATENT OFFICE.

FREDERICK K. LORD, OF BAYONNE, NEW JERSEY.

INTERNAL-COMBUSTION ENGINE.

1,237,350.

Specification of Letters Patent. Patented Aug. 21, 1917.

Application filed November 8, 1915. Serial No. 60,208.

To all whom it may concern:

Be it known that I, FREDERICK K. LORD, a citizen of the United States, residing at Bayonne, county of Hudson, and State of New Jersey, have invented a certain new and useful Improvement in Internal-Combustion Engines, of which the following is a specification.

My invention relates to internal combustion engines and has for its principal object the production of a symmetrical structure and one in which the sides of the engine casing will not be encumbered by shafting, gearing, etc.

This and further objects will more fully appear in the following specification and accompanying drawings, considered together or separately.

In the drawings,

Figure 1 is a transverse sectional view of an internal combustion engine embodying my invention, provided with a rear starter, and with a magneto carried on the top of the crank casing and inclosed by the rear starter mechanism, the section being taken on the line 2—2 of Fig. 2.

Fig. 2 is a side elevation of the rear end of an engine partly in section; and

Fig. 3 is a detail plan view of a portion 30 of the apparatus.

In the above views, similar reference characters designate like parts in all the several figures.

In the drawings, 1 designates the crank 35 shaft of an internal combustion engine embodying the invention, 2 is a clutch of any well known type, 3 is a lever by means of which the clutch may be manipulated and 4 is a propeller shaft. The crank shaft 1 is 40 mounted in suitable bearings in a crank casing composed of a lower member 5 and an upper member 6. The crank casing also incloses the clutch and the major portion of its operating devices. Mounted on the top 45 of the member 6 is a cylinder 7, said cylinder being provided with a water jacket as is usual.

Carried on the crank shaft 1 and in proximity to the clutch 2 is a sprocket wheel 8. A sprocket pinion 9 is supported in an A 50 shaped standard 10 which is bolted or otherwise secured to the top of the member 6, and a chain 11 passes over the sprockets 8 and 9. The chain passes through openings 55 12—13 in the top on the member 6. The standard 10 is mounted on the rear or after

end of the casing and behind the rearmost cylinder of the engine. The arbor 13 of the sprocket pinion 9 is carried in bearings in the upper part of the standard 10 and projects rearwardly and its rear end carries loosely mounted thereon a hand crank 14. The arbor 13 is provided with a projection 15 which is engaged by an angle slot in the hub of the hand crank so that by movement 60 of the crank in one direction the arbor will be rotated and the rotation of the arbor in the other direction will not move the crank. The sprocket wheels 8 and 9, chain 11 and crank 14 constitute a "rear starter" by means 65 of which the engine may be turned over by hand usually utilized to accomplish the preliminary compression and explosion of the fuel.

Carried on the top of the member 6 of the 75 crank casing is a magneto-electric machine or other electro-mechanical current generating device 16. In the embodiment of the invention illustrated, a magneto is located between the legs of the standard 10 so that 80 it occupies the same space on the top of the casing as does the standard, and requires no additional space.

Carried on the crank shaft 1 near its connection with the clutch is a spur pinion 17 85 which forms the first member of a train of gearing to the magneto, as at 18, to a water circulating pump 19, as at 20, and to an oil circulating pump 21, as at 22.

A conductor 23 extends from the magneto 90 16 to a spark plug 24 on the cylinder. The conductor is supported at intervals by means of insulating bridge pieces 25 and 26 and the natural stiffness of the wire will hold it out of contact with metallic parts of the engine. 95 The magneto and all of the rear starter, except the crank 14, are inclosed in a casing 27 so that none of the moving parts of the apparatus will be exposed.

The sprocket wheel 8 is supported in the 100 following manner: The lower member 5 of the crank casing is provided with a partition 28 and the upper member 6 with a partition 29. These partitions form a bulkhead through which the crank shaft 1 passes. 105 Mounted on one side of the bulk head is an annular journal 30 which encircles the hub of the crank shaft member of the clutch 2 and on which the sprocket wheel 8 is loosely mounted. The hub of the sprocket 110 wheel is provided with ratchet teeth 31. The crank shaft member of the clutch carries a

series of pawls 32 adapted to engage the teeth 31. A stop 33 is carried by the clutch member in proximity to each pawl and acts to limit the movement of the pawl against centrifugal force.

In starting the engine the sprocket wheel 8 is rotated in the clockwise direction in Fig. 1. The teeth 31 will engage such pawls as will by gravity rest upon the hub of the wheel and the crank shaft will be rotated to secure the initial compression in the cylinders. When the explosion occurs the shaft 1 will be turned over in the same direction and the engine will start under its own power. When the crank shaft is running, the centrifugal force will raise the pawls 32 from engagement with the hub of the wheel 8 against the stops 33 so that the sound of the pawls riding over the ratchet teeth will be eliminated.

While I have shown a magneto as carried on the casing and occupying the same space thereon as does the rear starter, it will be understood that instead of the magneto a dynamo for charging a set of storage batteries may be used in the same manner.

While I have shown the standard 10 as A-shaped, having two legs, it is to be understood that such standard need not necessarily be so shaped, nor need it have two legs.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:

1. An internal combustion engine having a crank shaft, a crank casing, a chain wheel coöperating with the shaft, a manually operated chain wheel carried above the casing, a chain passing over the wheels, and a magneto mounted on top of the casing and extending within the loop of the chain.

2. An internal combustion engine having a crank shaft, a crank casing, a chain wheel within the casing and coöperating with the shaft, a standard carried on the top of the casing, a manually operated chain wheel carried by the standard, a chain passing through the casing over the wheels, and a magneto mounted on the casing and extending within the space occupied by the standard.

3. An internal combustion engine having a crank shaft, a crank casing, a chain wheel coöperating with the shaft, an open standard on the top of the casing, a chain wheel carried by the standard, a chain passing around

the wheels, and a magneto mounted on the top of the casing and extending within the standard.

4. An internal combustion engine having a crank shaft, a crank casing, a chain wheel within the casing coöperating with the shaft, an A shaped standard on the top of the casing, a manually operated chain wheel carried by the standard, a chain passing through the casing and around the wheels, and a magneto mounted on the top of the casing and extending between the legs of the standard.

5. An internal combustion engine having a crank shaft, a crank casing, a chain wheel coöperating with the shaft, a standard carried on the top of the casing, a chain wheel carried by the standard, a chain passing over the wheels, and a magneto mounted on the casing and within the space occupied by the standard.

6. An internal combustion engine having a crank shaft, a crank casing, a chain wheel coöperating with the shaft, an open standard on the top of the casing, a chain wheel carried by the standard, a chain passing around the wheels, and a magneto mounted on the top of the casing and disposed within the standard.

7. An internal combustion engine having a crank shaft, a crank casing, a chain wheel coöperating with the shaft, an A shaped standard on the top of the casing, a chain wheel carried by the standard, a chain passing around the wheels, and a magneto mounted on the top of the casing and disposed between the legs of the standard.

8. An internal combustion engine having a crank shaft, a crank casing, a chain wheel coöperating with the shaft, a manually operated chain wheel carried outside of the casing, a chain passing through the casing and coöperating with the wheels, and a magneto mounted on the exterior of the casing, a part at least of the magneto extending within the loop formed by the chain.

9. An internal combustion engine having a crank shaft, a crank casing, a chain wheel coöperating with the shaft, a chain wheel carried outside the casing, a chain coöperating with the wheels, and a magneto mounted on the exterior of the casing, a part at least of the magneto lying within the loop formed by the chain, and a casing surrounding the magneto and chain.

This specification signed and witnessed this fifth day of November, 1915.

FREDERICK K. LORD.
